J. A. NOTT.
SLIDING SUPPORT FOR TYPEWRITERS.
APPLICATION FILED AUG. 22, 1919.

Patented Aug. 22, 1922.

Inventor:
J. A. Mott,
By Chamberlain, Greenleaf & Atlys:

UNITED STATES PATENT OFFICE.

JOHN A. NOTT, OF CHICAGO, ILLINOIS, ASSIGNOR, BY MESNE ASSIGNMENTS, OF ONE-HALF TO IRA KRUPNICK, OF CHICAGO, ILLINOIS.

SLIDING SUPPORT FOR TYPEWRITERS.

1,426,762.

Specification of Letters Patent. Patented Aug. 22, 1922.

Application filed August 22, 1919. Serial No. 319,082.

To all whom it may concern:

Be it known that I, JOHN ARTHUR NOTT, a subject of the King of Great Britain and Ireland, residing at Chicago, county of Cook, State of Illinois, have invented a certain new and useful Improvement in Sliding Supports for Typewriters, and declare the following to be a full, clear, and exact description of the same, such as will enable others skilled in the art to which it pertains to make and use the same, reference being had to the accompanying drawings, which form a part of this specification.

My invention has for its object to produce a simple and novel cushioning support for a typewriter which will permit it to be accurately aligned upon a typewriter desk and slide back into an idle position when the supporting table is tilted for the purpose of closing the desk.

A further object of the present invention is to produce a simple and novel hook or stop device adapted to be mounted upon a typewriter for co-operation with a sliding support which, by the substitution of one simple part for another, can be applied to any one of a great variety of types of typewriters.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a side elevation of the lower portion of a typewriter frame equipped and supported in accordance with the present invention, the supporting table being shown in section;

Fig. 2 is a section taken approximately on line 2—2 of Fig. 1;

Fig. 3 is a top plan view of one of the stationary guides and sliding supporting cushion, together with the corresponding stationary stop;

Fig. 4 is a rear view of the stop member carried by the typewriter frame, modified for use on a typewriter of a different construction from that illustrated; and

Fig. 5 is a side elevation of the device shown in Fig. 4.

Referring to the drawing, 1 and 2 represent two long channels or troughs which

are preferably stamped out of metal but may be otherwise formed; these members being adapted to be secured upon the table of a typewriter desk so as to lie parallel with each other and at right angles to the front edge of the table; the distance between the longitudinal centers of the troughs or channels being the same as the distance between the centers of the supporting feet or opposite sides of the typewriter to be supported. Within each trough is an elongated sliding cushion considerably shorter than the trough but long enough to span the two supporting feet on one side of the typewriter. In the arrangement shown, each cushion is made up of an under layer, 3, of felt and an upper layer, 4, of rubber, cemented or otherwise secured together. Underlying each cushion and extending upwardly between one or both sides thereof and the sides of the corresponding trough or channel, is a layer, 5, of felt or other suitable material which will prevent the cushion from sticking to the sides of the channel or trough. The parts are so proportioned that the cushion with its partial envelope, 5, has a sliding fit in its trough or channel so that there will be no lateral play between the cushion and the trough or channel while, at the same time, the cushion may be moved freely in the lengthwise direction. The top of the cushion preferably lies somewhat below the upper edges of the sides of the trough or channel, while the side members of the envelope or sheathing, 5, preferably extend slightly above the trough or channel.

If the feet of the typewriter do not happen to be of the proper size I substitute therefor feet, 6, preferably of rubber, flat on the bottom and of a diameter substantially the same as the width of the cushion. Therefore, after the two troughs or channels have been properly fastened upon the table, indicated at 8, and the cushions placed therein, the typewriter, of which a part of the frame 7 is illustrated, may be mounted with its four feet resting on the two cushions; the feet extending somewhat downwardly into the troughs so that the upper portions of the sides of the latter prevent lateral displacement of the typewriter; and the uppermost portions of the sides of the sheathing, 5, being interposed between the side walls of the troughs or channels and

the rubber feet so as to prevent the latter from adhering to the sides of the troughs and permitting a free sliding movement of the cushions and typewriter as a single 5 unit when it is desired to cause the typewriter to move toward the back or toward the front.

The movement of the typewriter in one direction, namely toward the rear in the 10 example illustrated, is through the action of gravity when the table of the desk is tilted during the process of closing the desk and therefore it is necessary that some kind of a stop be provided to limit the automatic 15 shifting of the typewriter. There are preferably two of such stop devices, one on each side of the typewriter, and each necessarily comprises a stationary part and a part movable with the typewriter. The stationary 20 member of my improved stop preferably consists of a block, 9, having thereon a forwardly and upwardly-projecting finger, 10. Each block is adapted to lie beside one of the guiding and supporting 25 channels or troughs and is preferably interlocked with the latter so as to permit the block to be held firmly in place by means of a single screw. In the arrangement shown, each block has a laterally-projecting tongue, 30 11, adapted to extend into a longitudinal groove, 12, of the corresponding channel or trough. The groove, 12, is preferably made longer than the block so as to permit the latter to be adjusted relatively to the trough 35 or channel in the longitudinal direction. This permits the supporting and guiding elements to be attached to the table and the stationary stops to be adjusted thereafter without making it necessary to shift the 40 supporting and guiding elements. After the blocks have been properly located each may be fixed in place by means of a screw, 13, passing down through the same and into the table. By placing the screw at the opposite 45 end of the block from that from which the finger 10 projects, any force applied to the finger and tending to lift the block will be borne largely by the corresponding guiding channel or trough due to 50 the interlocking connection between the two, instead of being borne wholly by the screw 13.

The stop member carried by the typewriter consists of an inclined fin or ear, 55 14, adapted to project laterally into the plane of the inclined finger and to pass underneath the latter as the typewriter slides back, so that the finger exerts a wedging action on the traveling stop member, tending 60 to force it downwardly and thus holding the typewriter firmly to its support after it has traveled back as far as it can go. The stop member 14 must be attached to some part of the frame of the typewriter and, 65 since typewriters of different makes have

differently shaped frames, it is necessary that a variety of attaching means are required. The part 14 should remain the same, regardless of the make of the typewriter and therefore, in order to simplify 70 and cheapen the manufacture, I make the traveling stop member in two parts, one of which is universal in its application while the other may be replaced by a substitute part according to the style of typewriter 75 which is being fitted. In the arrangement shown, the element 14 is arranged on the lower end of a vertical plate, 15, having at the top an outwardly and laterally-directed flange, 16, inclined from front to rear in the 80 opposite direction from the inclination of the element 14. The other half of the device consists of a plate, 17, having a flange, 18, complementary to and adapted to rest upon the flange, 16, and having at the upper end 85 a hook, 19, adapted to extend over the top of the side bar of the lower portion of the typewriter frame. The two parts of the stop device are held together by a bolt, 20, which passes through the element 14, 90 through the flanges 16 and 18, and through a portion of the element 19. At the lower end of the part 20 is a hook, 21, adapted to engage with the under edge of the side bar of the typewriter frame. On the upper end 95 of the member 20 is a nut, 22. It will be seen that when the parts are assembled as shown in Figs. 1 and 2, the nut, 22, being screwed down, the stop device is firmly clamped upon the typewriter. 100

Where the frame of the typewriter is different from that herein illustrated, a differently shaped piece is substituted for the part 17 with its hook 19. Thus, as shown in Figs. 4 and 5, the member that co- 105 operates with the part of the stop carrying the ear 14 may consist of a plate, 24, lying against the inner side of the plate 15 and having an outwardly directed flange, 25, which overlies the flange 16; there being at 110 the lower end of the plate 24 an inwardly-directed flange, 25. This modified form of stop is fastened to the typewriter by means of a bolt, 26, passing through aligned holes in the plates 15 and 24. Only a single bolt 115 is required because the engaging flanges 16 and 25 serve to lock the two halves of the stop together after the bolt is in place.

While I have illustrated and described with particularity only a single preferred 120 form of my invention, I do not desire to be limited to the exact structural details thus illustrated and described; but intend to cover all forms and arrangements which come within the terms employed in the definitions of my invention constituting the appended claims.

I claim:

1. A stop adapted to be attached to a typewriter frame comprising two members 130

each having a vertical body portion and a laterally-projecting flange, said flanges being upwardly inclined from the front edge to the rear edge of the device and lying in contact with each other, one of said members having a part adapted to engage with a typewriter frame, and the other of said members having a projecting ear for engaging with a stationary stop, and a single fastening device adapted to pass through said members to hold them clamped together and to the typewriter frame.

2. In an apparatus of the character described, a stationary supporting guide, a stationary stop arranged beside and interlocked with said guide, a single screw for fastening said stationary stop to a support, and a movable stop adapted to be fastened to a typewriter and co-operate with said stationary stop to limit the movement of the typewriter along said guide.

3. In an apparatus of the character described, two stationary parallel channel-shaped guides, cushions slidably fitted in said guides so as to be movable lengthwise thereof and each having a thickness less than the depth of the corresponding channel, a member to be supported, and supporting elements on said member resting on said cushions and having a width approximately equal to the interior width of the guides.

4. In an apparatus of the character described, two stationary parallel channel-shaped guides, cushions slidably fitted in said guides so as to be movable lengthwise thereof and each having a thickness less

than the depth of the corresponding channel, a member to be supported, and rubber feet on said member resting on said cushions and having a width approximately equal to the interior width of the guides.

5. A stop adapted to be attached to a typewriter frame comprising two members each having a vertical body portion and a laterally-projecting flange, a stationary stop, one of said members having a part adapted to engage with a typewriter frame, and the other of said members having a projecting ear for engaging with a stationary stop, and a single fastening device adapted to pass through the flanges on said members and having a part thereon adapted to engage with said frame so as to clamp said members together and to the typewriter frame.

6. In an apparatus of the character described, a stationary channel-shaped guide, a channel-shaped piece of felt lying within said guide and movable lengthwise of the latter, and a cushion fitting within the channel of the felt and having a thickness less than the depth of the channel in the felt.

7. In an apparatus of the character described, a stationary channel-shaped guide, a channel-shaped piece of felt considerably shorter than the guide lying within the guide and movable lengthwise of the latter, and a cushion fitting within the channel of the felt and movable with the latter.

In testimony whereof, I sign this specification.

JOHN A. NOTT.
